(57) **CLAIM**

The ornamental design for a vibratory roller, as shown and described.

DESCRIPTION

FIG. 1 is a front, top, left perspective view of a vibratory roller showing the new design;

FIG. 2 is a rear, top, right perspective view thereof;

FIG. 3 is a rear, bottom, left perspective view thereof;

FIG. 4 is a front elevation view thereof;

FIG. 5 is a rear elevation view thereof;

FIG. 6 is a left side view thereof;

FIG. 7 is a right side view thereof;

FIG. 8 is a top plan view thereof; and,

FIG. 9 is a bottom plan view thereof.

The broken lines of even length shown in the drawings illustrate portions of the vibratory roller that form no part of the claimed design.
